UNITED STATES PATENT OFFICE.

OSCAR KROEHLE, OF LAKEWOOD, OHIO, ASSIGNOR TO THE PROTEX SIGNAL COMPANY,
OF CLEVELAND, OHIO, A CORPORATION OF OHIO.

DESIGN FOR THE FRONT FOR A TRAFFIC-DIRECTING SIGNAL LAMP.

Application filed September 12, 1921. Serial No. 500,214. Term of patent 3½ years.

To all whom it may concern:

Be it known that I, OSCAR KROEHLE, a citizen of the United States, residing at Lakewood, in the county of Cuyahoga and State of Ohio, have invented a new, original, and ornamental Design for the Front for a Traffic-Directing Signal Lamp, of which the following is a specification, reference being had to the accompanying drawing, forming part thereof.

The drawing is a view of the front for a traffic-directing signal-lamp, showing my new design.

I claim:

The ornamental design, substantially as shown, for the front for a traffic-directing signal-lamp.

OSCAR KROEHLE.
